UNITED STATES PATENT OFFICE.

FRED PARKER, OF OAKLAND, CALIFORNIA.

BUTTON-HOOK.

1,355,567.

Specification of Letters Patent. Patented Oct. 12, 1920.

Application filed July 9, 1918. Serial No. 244,003.

To all whom it may concern:

Be it known that I, FRED PARKER, citizen of the United States, residing at Oakland, in the county of Alameda and State 5 of California, have invented certain new and useful Improvements in Button-Hooks, of which the following is a specification.

This invention is a collar buttoner for buttoning a collar on a shirt.

10 The invention is illustrated in the accompanying drawing which forms a part of this specification and the appended claim.

Referring to the drawing:

Figure 1 is a view illustrating the buttoner engaging a collar button for buttoning the flap of the collar.

Fig. 2 is a view illustrating the buttoner in the act of buttoning the inner flap of the collar on the collar button.

20 Fig. 3 is a view illustrating the buttoner having buttoned both flaps of the collar and the buttoner ready to be disengaged from the collar button.

Fig. 4 is an end view of the hook end of 25 the buttoner.

Fig. 5 is an enlarged side view of the buttoner hook.

Fig. 6 is a view similar to Fig. 5 taken at 90 degrees to Fig. 5.

30 Fig. 7 is a view similar to Fig. 5 looking at the left side of the hook as shown in Fig. 5.

My collar buttoner comprises a shank 1, a screw shaped hook 2 on one end of said shank and a handle 3 on the other end of the shank.

The end portion 2' of the hook 2 is substantially at right angles to the shank 1 and is approximately half a complete turn, 40 which allows it to pass over the head of the collar button.

In order to button a collar with my buttoner, the hook 2 may be inserted through the button hole of one of the collar flaps 4 and hooked over the head 5 of the collar button 6; the flap 4 is then pressed inward so that the collar button head 5 and the screw hook engage the collar button hole in said flap; the handle 3 is grasped and the button hook is turned, causing the screw 50 hook to engage the flap 4 at the edge of its collar button hole and force the flap over the head of the button, the head passing through the collar button hole. The hook 2 may then be removed from the head of 55 the collar button for buttoning the other flap 7 of the collar. In order to button flap 7 of the collar, the hook 2 is inserted through the collar button hole in the flap 7 and again hooked over the head 5 of the collar 60 button; the flap 7 is then pressed inward and the collar button hook turned and the flap 7 is buttoned in the same manner as flap 4.

Having described my invention, I claim as new and desire to secure by Letters 65 Patent:

A collar buttoner including a shank, a hook, on the end of the shank, the end portion of the hook extending substantially at right angles to the shank to a point sufficient only to engage the head of the collar button, the rest of the hook being screw-shaped to enable the shank to be pulled and rotated to cause the screw-shaped hook portion to engage the collar button hole to draw the head of the collar button through the button hole.

In testimony whereof I affix my signature.

FRED PARKER.
